ELECTRIC TERMINAL AND CONDUCTOR MOUNTING

Filed May 17, 1949

Fig. 1.

Fig. 2.

Fig. 3.

A. R. Liaci

INVENTOR

BY *Catnow & Co.*
ATTORNEYS.

1 of the drawing, and a wire such as indicated in dotted lines is forced into one end of the plug to be connected with the plug, as the electric wire or cord strikes the inner ends of the plates 15, the plates are moved to the positions shown in dotted lines, whereupon they disengage the contact arms 9 allowing the spring tension of the arms to move the arms inwardly snapping the prongs 20 into insulation of the electric wire or cord to contact the wires thereof, completing a circuit.

Should it be desired to release the wire, it is only necessary to move the knobs 24 outwardly, whereupon the prongs 20 will become disengaged from the electric cord, and since the plates are forced against the free ends of the contact arms, by the action of the springs 22, it is obvious that when the tongues 19 fall opposite to the openings 17 of the plates, they will snap into the openings, holding the plates in a set position as shown in full lines in Fig. 1, ready for actuation to complete a circuit with an electric cord forced into one end of the plug, as previously described.

From the foregoing it is believed that due to the construction shown and described, the operation and construction of the electric plug will be clearly understood, and that further description as to the operation and utility of the plug is unnecessary.

Having thus described the invention, what is claimed is:

In an electrical fitting, a body having a central longitudinal passageway extending inwardly

from one end thereof, into which an electric cord is inserted, contact fingers extending into said body from the opposite end thereof, a pair of spaced yieldable contact arms mounted within the body at opposite sides of said longitudinal passageways and biased toward each other, tongues extending from the ends of said contact arms, said contact arms including leg portions in circuit with said contact fingers, plates, having openings, pivotally connected with said leg portions, the tongues of said contact arms being removably held within the openings of said plates, said plates normally extending across said passageway and moved by the electric cord inserted in the passageway, whereby said plates are disengaged from said contact arms, releasing the contact arms for movement towards each other, and contact prongs extending inwardly from said contact arms adapted to pierce the electric cord extending through the passageway, completing a circuit with the cord as the contact arms move towards the electric cord.

ANGELO R. LIACI.
